UNITED STATES PATENT OFFICE.

LEONARD DEE STEPHENSON, OF NEW YORK, N. Y., ASSIGNEE, BY MESNE ASSIGNMENTS, TO AMERICAN PAPER BOTTLE AND CAN COMPANY, INC., OF WILMINGTON, DELAWARE, A CORPORATION OF DELAWARE.

MACHINE FOR CAPPING MULTISIDED PAPER BOTTLES.

1,349,234.

Specification of Letters Patent. Patented Aug. 10, 1920.

Application filed November 15, 1917. Serial No. 202,178.

To all whom it may concern:

Be it known that I, LEONARD DEE STEPHENSON, a citizen of the United States, and resident of the borough of Manhattan, 5 in the city and State of New York, have invented a new and useful Improvement in Machines for Capping Multisided Paper Bottles, of which the following is a specification.

10 The object of my invention is to provide a machine for applying metal caps to multisided paper bottles, and is particularly directed to machines for applying the bottom caps to said multi-sided paper bottles.

15 My invention comprises certain improvements in machines for capping multisided paper bottles in which the outer uprising walls of the metal cap are crimped against the bottom side walls of the bottle by the 20 action of crimping jaws, means being employed for ejecting the capped paper bottle after the crimping jaws have been opened; the movement of the crimping jaws and the 25 bottle ejecting means being controlled by a common cam having crimping jaw controlling surfaces and ejecting means controlling surfaces.

A practical embodiment of my invention is represented in the accompanying drawings in which,

Figure 1 represents the machine in top plan.

Fig. 2 is a view of the machine in side elevation.

35 Fig. 3 is a section taken in the plane of the line III—III of Fig. 2.

Fig. 4 is a section taken in the plane of the line IV—IV of Fig. 1, with the parts in one position.

40 Fig. 5 is a similar section in detail, showing the parts in another position.

Fig. 6 is a detail section showing the metal cap inserted in the bottom of the multisided paper bottle before the cap is secured 45 thereto, and

Fig. 7 is a similar view showing the cap secured to the bottle.

The table 1 of the machine is spaced from the base 2 by suitable legs 3. A horizontal 50 drive shaft 4 is mounted in suitable bearings 5 and is provided at its inner end with a bevel gear 6. A centrally arranged member 7 is supported by the table 1, and extends both above and below the table. The upper

extension 8 has the same number of sides as 55 the multi-sided paper bottle 9, and fits snugly within the depending side walls 10 of the metal cap 11. This member 7 forms a journal 12, immediately under the table 1, for a cam 13, forming part of a bevel gear 60 14, the teeth of which mesh with the teeth of the bevel gear 6 on the drive shaft 4. A nut 15 having a screw-threaded engagement with the lower end of the member 7, serves to support the cam 13 in close proximity to 65 the under side of the table 1.

Crimping jaws 16, corresponding in number to the number of sides of the paper bottle, are mounted to slide on the table 1 and are adjustably connected by bolts 17 to 70 blocks 18 slideable in slots 19 in the table. These blocks 18 are provided with cam studs or rollers 20 located within a cam groove 21 in the upper side of the cam 13. The shape of this cam groove is such that all of the 75 crimping jaws will be opened and closed simultaneously. As the jaws are closed, they will force the uprising outer side walls 22 of the metal cap inwardly to clamp the bottom sides of the paper bottle snugly between 80 the inner and outer side walls of the cap to lock the cap to the bottle.

An ejecting plunger 23 is slidably mounted in the member 7 and it is provided with a head 24 which is moved into and out of a 85 corresponding recess 25 in the projecting upper end of the member 7. The lower end of the plunger 23 projects beyond the nut 15.

An ejector controlling lever is pivoted at 26 to lugs 27 uprising from the base 2, one 90 arm 28 of which lever engages the bottom end of the plunger 23 and the other arm 29 of which lever is arranged in position to be engaged at the proper times by cam surfaces on the under side of the cam 13. A coil 95 spring 31 is interposed between the lower end of the member 7 and a fixed collar 32 on the lower end of the plunger 23, which spring insures the holding of the arm 29 up into the path of the cams 30 and also insures the depression of the plunger 23 to bring its head 24 into a recess 25 in the member 7.

In operation, the metal cap is placed on the upper projecting end of the member 7, and 105 the open bottom of the multi-sided paper bottle is inserted between the inner and outer side walls of the cap. The crimping jaws

are closed by the rotary movement of the cam 13 to crimp the bottom sides of the bottle between the inner and outer side walls of the cap. The jaws are then opened by the further rotary movement of the cam 13 and the ejecting plunger 23 is then raised to lift the bottle off from the table where the bottle may be readily removed.

From the above description it will be seen that a very simple and effective means has been devised for capping the bottle and for ejecting the capped bottle, a common cam being provided for controlling the movements of the crimping jaws and ejecting means, said cam also forming a member of the bevel gear controlled by the drive shaft.

It is evident that various changes may be resorted to in the form, construction and arrangement of the several parts without departing from the spirit and scope of my invention, and hence I do not wish to limit myself to the construction herein described, but

What I claim is:

1. In a machine for securing metal caps to multisided paper bottles, a table having a projection fitting within the cap, crimping jaws movable along the table, an ejector working through the table, and a cam rotating underneath the table for controlling the movements of the jaws and the ejector.

2. In a machine for securing metal caps to multi-sided paper bottles, a table having a projection fitting within the cap, crimping jaws movable along the table, an ejector working through the table, a cam rotating underneath the table for controlling the movements of the jaws and the ejector, and a drive shaft geared to the cam.

3. In a machine for securing metal caps to multisided paper bottles, a table having a projection fitting within the cap, crimping jaws corresponding in number to the number of sides of the bottle, movable along the table, an ejector working through the table,

and a cam rotating underneath the table for controlling the movements of the jaws and the ejector.

4. In a machine for securing metal caps to multisided paper bottles, a table having a projection fitting within the cap, crimping jaws corresponding in number to the number of sides of the bottle, movable along the table, an ejector working through the table, a cam rotating underneath the table for controlling the movements of the jaws and the ejector, and a drive shaft geared to the cam.

5. In a machine for securing metal caps to multisided paper bottles, a table having a projection fitting within the cap, crimping jaws movable along the table and having depending studs or rollers, an ejector plunger working through the table, its operating lever, and a cam rotating underneath the table, having a groove in its upper side for receiving said studs or rollers to control the movements of the jaws, and one or more cam surfaces on its under side for engaging said ejector lever to control the movements of the ejector plunger.

6. In a machine for securing metal caps to multisided paper bottles, a table having a projection fitting within the cap, crimping jaws movable along the table and having depending studs or rollers, an ejector plunger working through the table, its operating lever, and a cam rotating underneath the table, having a groove in its upper side for receiving said studs or rollers to control the movements of the jaws, one or more cam surfaces on its under side for engaging said ejector lever to control the movements of the ejector plunger, and a drive shaft geared to the cam.

In testimony, that I claim the foregoing as my invention, I have signed my name this 31st day of October, 1917.

LEONARD DEE STEPHENSON.
